UNITED STATES PATENT OFFICE

153,538

DESIGN FOR A HAT

Jack L. Moore, Lawton, Okla.

Application September 2, 1947, Serial No. 141,171

Term of patent 14 years

(Cl. D3—13)

To all whom it may concern:

Be it known that I, Jack L. Moore, a citizen of the United States, residing at Lawton, in the county of Comanche and State of Oklahoma, have invented a new, original, and ornamental Design for Hat, of which the following is a specification, reference being had to the accompanying drawing, forming part thereof.

Figure 1 is a perspective view of a hat, showing my new design;

Figure 2 is a top plan view;

Figure 3 is a front elevation.

The characteristic feature of my design for a hat resides in the configuration of the crown which presents a relatively wide, elongated and shallow dished top portion bounded on its sides by substantially straight parallel ridges, with elongated side indentations extending from end to end of the crown, the longitudinal extremities of said top portion being bounded by transverse ridges and having transverse indentations in the adjacent front and rear portions of the crown,

the extremities of said front and rear indentations terminating in close proximity to the adjacent extremities of respective side indentations, all as shown.

I claim:

The ornamental design for a hat, as shown and described.

JACK L. MOORE.
